UNITED STATES PATENT OFFICE

170,601

SCARF

Vsevolode Nicouline, Milan, Italy, assignor to Edgar C. Hyman Co., Inc., New York, N. Y., a corporation of New York

Application April 28, 1953, Serial No. 24,727

Term of patent 7 years

(Cl. D3—12)

To all whom it may concern:

Be it known that I, Vsevolode Nicouline, a citizen of the Republic of Italy, and a resident of Milan, Italy, have invented a new, original, and ornamental Design for a Scarf, of which the following is a specification, reference being had to the accompanying drawing, forming a part hereof.

The figure is a plan view of a scarf showing my new design.

I claim:

The ornamental design for a scarf, substantially as shown.

VSEVOLODE NICOULINE.
